GLOVE AND FUR SEWING MACHINE.

1,426,472.

Specification of Letters Patent. Patented Aug. 22, 1922.

Application filed November 1, 1919. Serial No. 335,087.

To all whom it may concern:

Be it known that I, ALFRED GRIEB, a citizen of the United States, residing at Elizabeth, in the county of Union and State of New Jersey, have invented certain new and useful Improvements in Glove and Fur Sewing Machines, of which the following is a specification, reference being had therein to the accompanying drawings.

10 This invention relates to overedge sewing machines particularly of the type adapted for sewing furs and gloves.

A particular object of the invention is to provide a new and improved looper-operating mechanism for this type of machine which will insure the enchainment of the thread-loops. This is attained by looper-operating mechanism which produces a dwell or very slow movement of the looper 20 while it is holding the thread-loop spread and in position for the entrance of the needle, and until the needle has safely entered the loop, and which gives a rapid movement of the looper as it enters the loop 25 presented by the needle.

Another object of the invention is to provide means whereby the amount of movement of the looper and needle may be varied to adjust the machine for use in sewing both 30 heavy and light material, thus doing away with the necessity of having two or more different machines.

A further object of the invention is to provide looper-operating mechanism which 35 has a more direct and compact driving arrangement than those hitherto in use, thus rendering it more durable, giving quiet running, greater wearing qualities and speed.

The preferred embodiment comprises the 40 usual intermittently rotatable feed cups, by which the edges of the material to be united are fed to the stitching mechanism which comprises in the embodiment shown a horizontally reciprocating needle and a cooper- 45 ating looper.

The looper is vertically adjustable on a looper-bar which is fitted within a bearing bushing or sleeve mounted in a yoke fulcrumed upon a rocker member pivoted to 50 the frame-work of the machine. For imparting the rocking, or movement transverse the path of the needle, there is secured to the looper-bar adjacent the rear end thereof a crank provided with a ball-stud 55 fitting in a cam-groove formed in a disk mounted on the main-shaft. The horizontal

movements of the looper, that is in the direction of the needle-path, are imparted by means of a bracket secured to the looper-bar-bearing-bushing adjacent its rear end. 60 This bracket forms one end of a toggle driving mechanism, the other end of which mechanism is pivoted to one arm of a bell-crank-lever fulcrumed on the frame of the machine and having its other arm pivoted 65 to the end of a pitman driven from an eccentric on the main driving shaft. The pivot connection between the pitman and bellcrank-lever arm is adjustable to vary the effective length of this arm of the lever. 70 This bellcrank and toggle drive for the looper, together with the yoke fulcrumed on the rocker member give it its up and down movements. The arrangement of this direct driving means is such that a dwell 75 or slow movement is imparted to the looper when it is depressed on the needle side of the work to position the thread-loop for the entrance of the needle.

Referring to the accompanying drawings 80 for a more detailed description of the invention, Fig. 1 is an end elevation of the machine with a portion of the frame or casing broken away to show the interior mechanism. Fig. 2 is a plan view with the 85 cover removed. Fig. 3 is a partial front elevation with certain elements shown in section, the section being substantially on the line 3—3, of Fig. 1. Fig. 4 is a detailed sectional view of the toggle driving mechanism. Fig. 5 is a detailed sectional view of the connection between the needle-bar driving lever and needle-bar taken substantially on the line 5—5, Fig. 1. Fig. 6 is a side view of the mechanism shown in Fig. 5. 90 Fig. 7 is a detailed sectional view of the looper-bar and looper-bar bearing-bushing. Figs. 8, 9 and 10 are detailed views of the eccentrically mounted bearing stud for the connection between the driving pitmen and 100 the needle-bar driving lever and the looper-driving bellcrank-lever. Fig. 11 is a detailed view of the toggle driving mechanism taken on substantially the line 11—11, Fig. 1, looking in the direction of the arrow. 105

The machine comprises the frame or casting 1 extending transversely of which is the main driving shaft 2 journaled in bearings 3 in the frame and having the driving and hand pulleys 4 and 5 secured thereon. 110 The frame is pivotally mounted on the base-section 6.

Reciprocally mounted in bearings 7 and 8 in the upper part of the frame or casing 1 is the needle-bar 9. This needle-bar reciprocates in substantially a horizontal plane 5 as shown and is driven by the needle-bar driving lever 10 fulcrumed in the frame at 11 connected at the upper end of its longer arm to a clamp 12, secured on the needle-bar, by means of link 13. Connected to its shorter 10 arm is the driving pitman 14 carrying an eccentric strap coacting with the eccentric 15 on the main driving shaft. This pitman 14 is connected with the needle-bar driving lever by means of an eccentrically mounted bearing stud 16. The bearing stud 16 is secured in the lever 10 by means of a stud 17 mounted off center so that the stud is eccentrically mounted on the lever and by turning the bearing stud 16 on the stud 17 the 15 effective length of the driving arm of the lever 10 may be varied to vary the length of the stroke of the needle as is obvious. The bearing stud is secured in adjusted position by means of a pin 17' screwed in the member 20 16 at 17" and having its end 17''' entering a hole drilled in the bellcrank-lever arm. To the forward end of the needle-bar is secured the needle-clamp 18 carrying the needle 19.

30 The feeding mechanism comprises two cup-wheels 20 and 21 mounted so as to rotate in a horizontal plane. The feed-wheel 20 is mounted in bearings on the main frame 1 and is driven from the main driving shaft 2 35 by means of an eccentric 22 and a pitman 22' through suitable mechanism, not shown, which imparts thereto a step-by-step motion as is well known. The length of the intermittent motion and therefore the length of 40 the stitch may be adjusted by means of the adjustable link-clamp 22''. The presser-wheel 21 is mounted on a curved arm 23 pivoted to the main frame at 24 and is held in position with its edge coacting with the edge 45 of the wheel 20 by means of a spring 25 secured in the frame and bearing against a roller-stud 26 mounted on the extension of the arm 23 as shown at 27. The force of the spring 25 may be adjusted by means of the 50 adjusting screw 28. Presser-wheel 21 may be moved away from the feed-wheel 20 in order to insert the work therebetween by means of the lever 29 bearing on the under side of roller 26 and which may be operated 55 by a foot-treadle connected therewith by the rod 30. As shown in Fig. 1 the arm 23 extends upwardly and is bent over the line of seam-formation in order to leave sufficient and unobstructed space below the feed-cups 60 for the passage of the body of the work to be stitched. The wheel 21 is mounted upon the outer portion of the arm 23 by means of a stud 31 upon which it is freely rotatable. This wheel is secured in position by means 65 of a needle-guide clamp 32 which performs

the two functions of securing the cup-wheel in position and also providing a guide for the needle as shown at 32'. The member 32 being merely clamped upon the stud 31 may be adjusted to or from the wheel 21 thus 70 compensating for any wear which may occur therein and maintaining it at all times rigid upon its bearing stud.

The looper comprises a curved member 33 having at its lower end the hook 34 and at its 75 upper end is adjustably secured by a screw and slot connection at 35 upon the head 33' secured on the looper-bar 36 by means of screw 33''. The looper-bar 36 is fitted with-in a bearing sleeve or bushing 37 in such a 80 way that it may be oscillated therein by means of a crank 38 secured at the rear end of the looper-bar. The looper-bar driving crank 38 is provided with a ball-stud 39 fitting within a cam-groove 40 formed in the 85 disk 41 mounted upon the main driving shaft. Mounted at the front of the frame 1 is the shaft 42 upon which is pivoted the rocker 43 provided with upwardly extending arms 44 in which is fulcrumed the toggle 90 yoke 45. This yoke in the embodiment shown is curved over the needle-bar in substantially the form of an inverted U and is pivoted at its lower ends to the upper ends of the arms 44. At the upper part of this 95 curved portion is formed the bearing 46 in which the looper-bar bearing sleeve or bushing 37 is adjustably secured. The mechanism for reciprocating the looper comprises a toggle-bracket 47 which is clamped upon 100 the rear portion of the looper-bar bushing 37. This bracket 47 is provided with a bearing stud 48. Secured in the frame at 49 is a bearing stud 50 upon which is fulcrumed a toggle crank 51. This crank is provided 105 with an internal bearing 52. Reference character 53 designates a toggle driving link formed with a laterally extending bearing bushing or sleeve 54 at one end which is fitted upon the stud 48 and within the bearing 110 52 on the crank 51. Fulcrumed within the frame at 55 is a bellcrank 56 having the two arms 57 and 58. The arm 58 is pivotally connected at 59 to the other end of the driving link 53. The bellcrank-lever 56 is driven 115 from the main-shaft 2 by means of an eccentric 60 and its strap through the pitman 61. The connection between the pitman 61 and the arm 57 of the bellcrank-lever is adjustable to vary the effective length of the arm 120 57. This adjustment is secured by means of an eccentrically mounted bearing stud 16' the same as is employed at 16 between the pitman 14 and the bellcrank-lever 10 for driving the needle-bar.

Pivotedly supported on the top of the frame is the cover 62 carrying the usual spool-support 63, thread-tensioning means 64 and a thread-guide 65. This cover may be swung back on its pivot in order to give 130

access to the various driving mechanism within the frame.

Mounted upon the forward end of the needle-bar is the spring-pressed thread-nipper 56 released by means of the stud or pin 57 per 66 bearing upon the nipper-releasing plate 67 as clearly shown in Fig. 2. This nipper-plate is adjustably mounted on the bearing 68 by means of a screw and slot 69. Between the thread-guide 65 and the nipper 66 is the thread-control means 46'. This control means is mounted upon the yoke 46 so that its movements are imparted thereto and is used to take up the slack in the thread which would otherwise occur during the stitch-forming movement, thus giving a tighter stitch.

As the work to be stitched is fed between the adjacent portions of the cup-wheels 20 and 21 it is guided and held for stripping the needle by means of a fixed guide 70 secured upon the frame 1 extending outwardly and bent so that its end is positioned immediately above the upper edge of the cup-wheels and terminating adjacent the path of the needle, as shown in Fig. 2.

In operation the overlapped edges of the work to be united by the overedge stitch are inserted between the feed cup-wheels 20 and 21 and are fed thereby across the path of the needle. After the needle penetrates the work the thread-loop presented thereby is entered by the hook 34 of the looper over the guide 32'. The looper and needle are then retracted, the looper carrying the loop in an arched path over the edge of the work and depressing it below this edge and holding it spread and in line with the path of the needle on its next stroke. In this position which is substantially that shown in Figs. 1 and 2 a dwell or very slow motion is given the looper by the mechanism described. The dwell in the transverse or rocking motion is produced by a suitably shaped cam-groove 40. In the position shown in Fig. 1 the connection between the link 53 and the bellcrank 56 is adjacent a straight line drawn through the center of the stud 48 upon which the link 53 is pivoted and the center 55 upon which the bellcrank 56 is fulcrumed. Thus it will be seen that as the arm 57 is raised by the pitman and eccentric the connection between members 53 and the arm 58 move for a short distance around the pin 48 as a center without imparting any appreciable movement to the looper-box bearing bushing 37. As the reciprocatory movement is caused by the motion of the link 53 and crank 51 about the pivot 50 and the up and down movement of the looper is caused by these members cooperating with the yoke 46 which rises and falls as its connection with the arms 44 of the rocker 43 move around the shaft 42 as a center it will thus be seen that a dwell or

very slight motion either across the center or in the up and down movement is produced and the thread-loop is thus held in that depressed position until the needle has safely entered the loop. By having the connection 59 move nearly on the line connecting the pivots 48 and 55 while the looper is depressed, the amount of movement required of the pivot 59 before imparting any appreciable motion to the looper may be increased, thus increasing the length of the dwell or time consumed in the slow movement. The up and down movement of the looper caused by the yoke 46 rising and falling as it moves with the rocker 43 about the pivot 42 is augmented by the up and down movement imparted to the rear end of the looper-bar by the toggle crank 51 as the stud or pivot 48 moves about the stud 50 as a center, the stud 48 being on the bracket 47 secured to the looper-bar-bushing 37.

A machine set to sew thin or light material is not adapted for sewing heavy material and therefore generally a separate machine adapted for such work is necessary. The present machine, however, is constructed so that it may be adjusted for sewing either light or heavy material as desired. When heavy material is fed between the cups 20 and 21 the seam being higher and thicker the looper is required to have a greater up and down movement or must move in an arched path of greater height when passing over the edge of the seam in order to clear the work than is required in sewing light material and it preferably should also have a greater movement cross-wise of the path of the material. The adjustment is accomplished first by turning the eccentrically mounted bearing stud 16' on its pivot through an arc of substantially 180° from that shown in Fig. 1. Thus as the supporting means is off center it will shift the center of the bearing stud toward the fulcrum 55 of the bellcrank-lever 56 thus shortening the effective length of the arm 57. As the driving eccentric 60 imparts the same motion to the pitman 61 as it did before, obviously the upper end of the arm 58 is given a greater movement about the fulcrum 55. This gives both greater horizontal movement to the looper-bar and greater up and down movement to the rear end thereof to which it is connected. These augmented movements are obviously imparted to the looper 33. However, in the embodiment of the invention illustrated as the rear end of the looper-bar is raised a greater amount, the hook 34 is dropped lower during the loop-entering movement and the whole looper 33 must therefore be reset to a higher position through its adjustable connection 35 on the looper-bar to compensate for this lower movement. This resetting of the looper hook brings it higher as it passes

over the edge of the work and thus gives greater clearance therebetween. Shifting of the pivot 16' also shifts to a certain extent the connection between the link 53 and the 5 arm 58 thus moving slightly the looper out of the corresponding relative position with respect to the needle transversely of the edge of the seam. This is controlled by a slight lengthwise adjustment of the looper-bar bushing. The length of the stroke of the needle may also be adjusted by rotating the bearing stud 16 between the pitman 14 and the needle-bar driving lever 10 in the same manner as the connection between the pitman 61 and the bellcrank-arm 57 as will be 10 15 obvious.

It will be seen that the driving mechanism for the looper is very compact and the drive is direct thus doing away with a large number 20 of parts and obviating lost motion which would necessarily result therefrom. By this direct drive arrangement the mechanism is more durable, has greater wearing qualities, is quiet running and may be operated at 25 high speeds.

Having thus set forth the nature of the invention, what I claim herein is—

1. In a sewing machine, in combination, 30 stitch-forming mechanism comprising a needle and looper, a looper-bar, a pivoted yoke for supporting the looper-bar, means for oscillating the looper-bar about its axis, toggle means connected to the looper-bar and adapted to reciprocate said bar and 35 with the yoke to impart up and down movements to the looper, and means for operating said toggle means.

2. In a sewing machine having a frame, in combination, stitch-forming mechanism comprising a needle and looper, a looper-bar, a yoke pivotally mounted in the frame and supporting the looper-bar, means for oscillating the looper-bar, toggle means for reciprocating said bar and with the yoke 40 45 imparting up and down movements to the looper, comprising a bracket connected to the bar, a toggle-crank fulcrumed on the frame and a toggle-link pivoted in the crank and on the bracket by concentric bearings and means for operating said link.

3. In a sewing machine having a frame, in combination, stitch-forming mechanism including a needle and looper, a looper-bar, a looper-bar-bushing in which the looper-bar 50 55 is sustained, means for oscillating the looper-bar, a yoke pivotally mounted in the frame and supporting the looper-bar-bushing, a bracket secured to said bushing, a crank fulcrumed on the frame, and a link pivoted to the bracket and crank and means for operating said link.

4. In a sewing machine having a frame and stitch-forming mechanism including a looper, means for operating the looper comprising a looper-bar, a yoke pivotally 60 65

mounted in the frame and sustaining the looper-bar, means for oscillating the looper-bar about its axis, a toggle-crank fulcrumed on the frame, a toggle-bracket connected with the looper-bar and having pivotal connection with the crank, a link having pivotal connection with the crank and bracket and means for operating said link. 70

5. In a sewing machine having a frame and stitch-forming mechanism including a looper, a looper-bar, means for oscillating the looper-bar about its axis, means for reciprocating and giving up and down movements to said looper-bar comprising a bracket connected with the looper, a crank fulcrumed in the frame, a toggle-link pivoted to the crank and bracket and means for operating said link comprising a bellcrank-lever fulcrumed in the frame and having an arm pivoted to the link and means for operating said bellcrank-lever. 75 80 85

6. In a sewing machine having a frame and stitch-forming mechanism including a looper, means for operating said looper comprising a yoke fulcrumed in the frame 90 and adapted to sustain the looper, a toggle-bracket connected with the looper, a toggle-crank fulcrumed in the frame, a toggle-link pivoted in the crank and on the bracket by concentric pivots, a bellcrank-lever fulcrumed in the frame and having pivot means connecting one arm thereof to the link and operating means connected to the other arm of the bellcrank-lever. 95

7. In an overedge sewing machine having 100 a frame, stitch-forming mechanism comprising a horizontally reciprocating needle, means for sustaining and feeding the edges of the work in the path of the needle, a looper cooperating with the needle in forming an overedge stitch, a looper-bar for sustaining the looper, a yoke fulcrumed in the frame, a looper-bar-bushing mounted in the yoke and sustaining the looper-bar, a crank secured on the looper-bar and cam means 105 cooperating therewith for oscillating the looper, a toggle-bracket secured to the looper-bar-bushing and provided with a bearing stud, a toggle-crank fulcrumed in the frame and provided with a bearing, a toggle-link 110 provided with a bearing sleeve fitted on the toggle-bracket stud and fitted in the bearing in the toggle-crank, a bellcrank-lever pivoted to the link and fulcrumed in the frame and means for oscillating the bellcrank-lever. 115 120

8. In a sewing machine having a frame and stitch-forming mechanism including a looper, means for operating the looper comprising a bracket connected with the looper 125 and have a bearing stud, a crank fulcrumed in the frame and provided with a bearing, a link having a bearing sleeve fitted on the stud and fulcrumed in the crank bearing and means for operating the link. 130

9. In a sewing machine comprising a frame and stitch-forming mechanism including a looper, a rocker-arm fulcrumed in the frame, a yoke pivoted to the rocker-arm, the rocker-arm being independent of any other driving means, a looper-bar sustained by said yoke, and means for operating said bar including a toggle-link drive, said elements being so constructed and arranged that the movements imparted thereby to the looper are compounded.
10. In a sewing machine having stitch-forming mechanism including a looper, means for operating the looper including a toggle-link-drive, power means, a bellcrank-lever having one arm connected with the toggle-link-drive and the other arm connected with the power means, and means for shifting the latter pivot so as to vary the effective length of the bellcrank-lever arm.
11. In an overedge sewing machine having stitch-forming mechanism including a needle and looper, means for sustaining and feeding the edges of the work to be united across the path of the needle, means for varying the amount of needle movement, means for imparting movement to the looper up and down and across over the said edges, said means being constructed to produce a dwell in the motion of the looper during the passage of the needle into the thread-loop positioned by the looper, and means for adjusting the looper operating means to vary the amount of the up and down and transverse movements of the looper.
12. In an overedge sewing machine having stitch-forming mechanism including a needle and looper, means for sustaining and feeding the edge of the work across the path of the needle, a looper-bar, means for adjustably mounting the looper on the looper-bar, means for operating the looper-bar to give the looper movement up and down and across over the edge of the work, said means being constructed to produce a dwell in the motion of the looper during the passage of the needle into the thread-loop positioned by the looper, and means for adjusting the latter means to vary the amount of the looper movements.
13. An overedge sewing machine having stitch-forming mechanism including a needle and looper, a main-shaft, means for sustaining and feeding the work across the path of the needle, needle-operating means and looper-operating means independently connected to the main shaft, and independent needle and looper adjustments whereby the needle and looper movements may be varied and coordinated to adjust the machine for different classes and thicknesses of work.
14. In a sewing machine having stitch-forming mechanism including a needle and looper, means for driving the needle and looper, needle adjusting means for adjusting the length of the movement of the needle, and means independent of the needle adjusting means for adjusting the length of movement of the looper to adapt the machine for different classes of work.
15. A sewing machine having stitch-forming mechanism including a needle and a looper, a main-shaft, operating means connecting the main-shaft with the needle, and means independent of the needle-operating means for connecting the main-shaft with the looper, said needle and looper operating means each including adjustable devices having two set positions of adjustment to adapt the machine for light and heavy work.
16. In a sewing machine having a frame and stitch-forming mechanism including a looper, a yoke mounted in the frame for bodily movement relative to the latter, a looper-bar sustained by the yoke, a looper-bar operating means and thread-control means carried by the yoke and bodily movable therewith.
17. In a sewing machine, stitch-forming mechanism including a needle and looper, a looper-support, means for reciprocating the needle, means for imparting up and down and reciprocatory movements to the looper and for causing the looper to dwell as the needle enters the thread-loop positioned by the looper, means for adjusting the needle reciprocating means to vary the amount of needle movement, means for adjusting the looper-operating means to vary the amount of looper movement, and means whereby the looper may be adjusted on its support.
18. In an overedge sewing machine, stitch-forming mechanism including a needle and looper, means for sustaining and feeding the edge of the work across the path of the needle, a looper-support, means for adjustably mounting the looper on the support, means for imparting movements to the looper up and down and across over the edge of the work and for causing the looper to dwell as the needle enters the thread-loop positioned by the looper, means whereby the amount of these looper movements may be varied, and means for varying the amount of the needle movements.
19. An overedge sewing machine having, means for sustaining and feeding the work, a reciprocating needle, a looper, a main-shaft, working connections between the main-shaft and the needle and looper operative to cause the looper to seize and present thread-loops from and to the needle alternately at positions on opposite sides of the work, and means for varying the amplitude of the needle stroke and for adjusting the looper mechanism to correspondingly vary

the distance between the loop-seizing and loop-presenting positions of the looper, thereby adapting the machine for sewing both light and heavy work.

- 5 20. An overedge sewing machine having, means for sustaining and feeding the work, a reciprocating needle, looper mechanism including a looper and means for moving it to seize and present thread-loops from and 10 to the needle alternately at positions on op-

posite sides of the work and up-and-down in an arched path across the edge of the work, the looper mechanism having provision for adjustment to vary the height of the arched path of motion of the looper between loop-seizing and loop-presenting positions at substantially constant levels. 15

In testimony whereof, I have signed my name to this specification.

ALFRED GRIEB.
